UNITED STATES PATENT OFFICE

JOHN F. METTEN, OF PHILADELPHIA, PENNSYLVANIA

VACUUM PUMP

Application filed March 19, 1930. Serial No. 436,922.

This invention relates to rotary vacuum pumps for withdrawing air and other gases from spaces that are required to be maintained at pressures considerably below atmospheric pressure at sea level and discharging the air or gases removed at or above atmospheric pressure. Pumps of this character have numerous applications in connection with power, process and pumping equipment 10 in steam stations, manufacturing plants, etc.

The early vacuum pumps of reciprocating and rotary displacement types which have been used are being discarded in favor of vacuum pumps operating on the jet principle 15 and using the kinetic energy of steam and water as the pumping medium by employing the entraining and compression principle of high velocity jets. In many processes the use of steam is objectionable due to its heating 20 action, and where it is used for higher vacuum it is necessary to carry out the work of withdrawal and compression to atmospheric pressure in a number of stages and to provide coolers between each stage to condense the 25 steam used in the preceding stage, to reduce the temperature and corresponding volume of the air or other gases moved.

In many cases water jet vacuum pumps are desirable on account of the absence of 30 heating action and also due to the fact that single stage pumps of this type are capable of providing comparatively high vacuum. The water jet ejector, however, requires a separate pump or other means for supplying 35 pressure water to the jet, and hence the combined efficiency is low owing to the combined hydraulic losses in the pump and ejector.

It is therefore the object of my invention to 40 produce a novel vacuum pump wherein the use of steam with its consequent heating is entirely eliminated and wherein no auxiliary pump to propel the water or to create compression is needed.

It is a further object of my invention to 45 provide a rotary vacuum pump which is capable of producing a relatively high vacuum and one which will operate at a relatively high index of efficiency.

To the above ends my invention consists of

a rotary head, a plurality of suction nozzles carried thereby, a water jacket surrounding said head, means for actuating said head, means for preventing the rotation of the water surrounding said head, and connections leading from said nozzles to the point where the vacuum is to be created. 55

My invention still further consists in various other novel features of construction and assembly all as hereinafter described and 60 claimed.

For the purpose of illustrating my invention I have shown in the accompanying drawings one form thereof which is at present preferred by me, since the same has been 65 found in practice to give satisfactory and reliable results, although it is to be understood that the various instrumentalities of which my invention consists can be variously arranged and organized and that my invention is not limited to the precise arrangement and organization of the instrumentalities as herein shown and described. 70

In the accompanying drawings:—

Figure 1 represents a view, partly in section and partly in elevation, of a novel vacuum pump embodying my invention. 75

Figure 2 represents a section on line 2—2 of Figure 1.

Figure 3 represents a section on line 3—3 of Figure 1. 80

Figures 4, 5 and 6 represent diagrammatic sectional views illustrating some of the principles underlying my invention and the mode of operation. 85

Figure 7 represents a longitudinal sectional view of a conventional water jet pump which may be helpful in describing and explaining the present invention.

Referring to the drawings in which like reference characters indicate like parts, 1 designates a vacuum pump embodying my invention and comprising the separating liquid tank or reservoir 2, to which is connected the runner chamber or jacket 3 by means of the upper and lower ports 4 and 5. 6 designates a stationary pipe leading from the point where the vacuum is to be created and extending downwardly into the chamber or jacket 3 where its lower end is engaged by the ex- 90

tension 7 of the rotary head or runner 8 which is carried by the shaft 9 which is journalled or provided with aligning bearings at 10 and driven by any suitable source of power as a driving motor or turbine 11. 5 The rotary head or runner 8 is provided with the nozzles 12 and the fan blades or vanes 13 and it communicates with the lower portion of the suction pipe 6 as will be understood from Figures 1 and 3. 14 and 15 designate annular passages corresponding to the circular path swept by the nozzles 12. The passages 14 and 15 are provided with the fixed blades or baffles 16 and 17 which serve to prevent the rotation of the liquid in which the rotary head or runner is immersed, which as will be seen from Figure 1, fills the chamber 3 and the tank 2 to the level 18. 19 designates a bottom bearing plate which is below and out of contact with the head or runner 8 and which carries the lower fixed blades 16 while 20 designates a stuffing box for the upper casing which encloses the lower portion of the pipe 6 and which carries the upper fixed blades 17. The runner chamber is preferably made in two upper and lower sections which are joined together at 21, said upper and lower sections being joined or secured to the tank 2 at 22, in order to facilitate manufacture and assembly. The nozzles 12 are elliptical in cross section (see Figs. 4-6) and have their major axis inclined to the plane of rotation of the runner 8. When the head or runner 8 is revolved, the angle of the nozzles 12 serves to impart to the surrounding liquid a relatively slow motion parallel to the axis of rotation as indicated by the arrows 23 in Fig. 4, the object of this being to prevent interference of the paths of the different nozzles 12 with respect to the liquid. While in the drawings I have shown only four nozzles 12 it is to be understood that a greater or less number of nozzles can be used depending on the duty required. 30 The flow of liquid relative to the rotating nozzles 12, results in the continuous withdrawal of the air or gas from the runner 8 and suction pipe 6. This action is similar in principle to that of the conventional water jet pump, illustrated in Fig. 7, except that the water or other liquid is nearly stationary and the eduction nozzles 12 are moving at a high speed relative to the liquid instead of the liquid moving at a high speed relative to said nozzles. There is an important advantage obtained in this transposition for the reason that the flow of gases, on account of their low density, can be induced at high speeds with small differences in pressure. 35 Consequently the moving nozzles 12, forming gas passages can be made of a contour calculated to reduce resistance due to motion of said nozzles through the liquid to minimum, and also to permit the withdrawal or entrainment of the removed air or gas to take place between two high velocity surfaces of the liquid relative to the nozzles instead of between the high velocity surfaces of the liquid and the stationary metal wall of the discharge tube in the conventional form of 40 water jet pump shown in Fig. 7 wherein the liquid jet is moving at high velocity and the eduction passage walls are necessarily stationary. Referring to Figure 6, it will be understood that when the nozzles 12 are moved through a liquid which is stationary in respect to the movement of said nozzles, the liquid flows or closes in at the following edges of the nozzles. The rate or velocity of this closing-in flow is approximately equivalent to the rate of acceleration of water particles due to the force of gravity and is therefore independent of the velocity of the moving nozzles. Consequently, if the velocity of the nozzles 12 through the liquid is 45 great enough with respect to the constant velocity of inflow referred to, there will be a vacuum cavity 26 of wedge section formed back of each nozzle, the length of which will increase in proportion to the velocity of the nozzles relative to the constant velocity of inflow. The inner surfaces of this vacuum space act as entraining surfaces and the air or gas is compressed to delivery pressure at the apex and passes upward with the vertical movement of the liquid in a spiral of small bubbles corresponding to the helical paths of the nozzles. This is due to the angle of the nozzles 12 and the translatory motion imparted to the liquid in which the runner or head is immersed. These bubbles separate out of the liquid and pass out through the 50 outlet 24 in top of separating tank 2. 55 Referring to Figure 5 it will be seen that if the speed of nozzles 12 is great enough to result in the length of vacuum cavity 26, greater than the distance (R) between a nozzle 12 and the juxtaposed guide blades, measured on the axis of said nozzle, a change in the pumping action takes place in that the 60 final compression of the air or gas withdrawn takes place after the apex of the vacuum cavity (S), has passed the ends of said guide blades, as a result of the vertical flow of the liquid in which the nozzles rotate. Where speeds can be adopted permitting this operating condition being obtained, the withdrawal capacity will be increased, since, instead of the volumetric capacity being dependent principally upon entrainment, it 65 would approach the volume of liquid swept through by the cross sectional area of said nozzles in a given unit of time. 70 In Fig. 7 I have shown a conventional water jet pump in which water is forced under pressure at the inlet end 27 which leads through the reduced nozzle 28 into the chamber 29. The chamber 29 is provided with a suction pipe 30 leading to the point where a vacuum is to be created. As the water passes 75

through the discharge end 31, the air in the chamber 29 is entrained and sucked with the water and discharged. The reduced pressure in the chamber 29 causes the air or other gas to flow thereinto through the suction pipe 30 which air is again entrained with the moving jet of water and is discharged through the nozzle 31.

My invention reverses the process to obtain the advantages above set forth by using a plurality of nozzles which move with respect to a relatively stationary liquid instead of forming a jet of water through the fixed discharge nozzle 31, the inner walls of which are stationary. The movement of my novel wedge shaped or conical nozzles creates a vacuum which "sucks" the air from the runner or head and the suction pipe 6.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention what I claim is new and desire to secure by Letters Patent, is:—

1. A rotary vacuum pump comprising a suction pipe, a runner casing, elliptical eduction nozzles immersed in a liquid, and communicating with said suction pipe, means for revolving said nozzles in a circular path in said liquid at an angle to their plane of rotation to produce suction at the outer ends of said nozzles, and means for separating the sucked gas from said liquid.

2. A rotary vacuum pump comprising a suction pipe, a sectional runner casing, a submerged rotating hollow runner communicating with said suction pipe, elliptical eduction nozzles carried by and communicating with said runner, said eduction nozzles being inclined at an angle to their plane of rotation and provided with terminal openings for discharging the air sucked from said suction pipe by the rotation of said nozzles, and upper and lower fixed blades in the upper and lower sections of said runner casing.

3. A vacuum pump comprising a suction pipe, a submerged rotating element communicating with said suction pipe and provided with elliptical nozzles having their major axes inclined to their plane of rotation, said nozzles being provided with peripheral discharge outlets so arranged that the movement of said nozzles relative to the surrounding liquid produces a continuous suction at said outlets, to entrain the contents of said suction pipe.

4. In a vacuum pump, a separating tank adapted to contain a liquid, a runner casing connected at its upper and lower portions to

and communicating with said tank, the latter having an outlet at the top thereof, aligning bearings in said casing, a shaft mounted in said bearings, a rotary element fast on the lower end of said shaft, fixed blades above and below said rotary element for preventing rotation of the liquid in which said rotary element is immersed, and a stationary suction pipe having its lower portion enclosing the lower portion of said shaft and opening into said rotary element.

5. In a vacuum pump, a separating tank adapted to contain a liquid, a runner casing connected at its upper and lower portions to and communicating with said tank, the latter having an outlet at the top thereof, aligning bearings in said casing, a shaft mounted in said bearings, a rotary element fast on the lower end of said shaft, fixed blades above and below said rotary element for preventing rotation of the liquid in which said rotary element is immersed, and a stationary suction pipe having its lower portion enclosing the lower portion of said shaft and opening into said rotary element, the bottom of said runner casing being detachable from the upper portion thereof and from the bottom of said tank.

6. In a vacuum pump, a separating tank adapted to contain a liquid, a runner casing composed of upper and lower sections connected at its upper and lower portions to and communicating with said tank, the latter having an outlet at the top thereof, aligning bearings in said casing, a shaft mounted in said bearings, a rotary element fast on the lower end of said shaft, fixed blades in said upper and lower casing sections above and below said rotary element for preventing rotation of the liquid in which said rotary element is immersed, a stationary suction pipe having its lower portion enclosing the lower portion of said shaft and opening into said rotary element, and means for actuating said rotary element and its shaft.

7. In a vacuum pump, a separating tank adapted to contain a liquid, a runner casing composed of upper and lower sections connected at its upper and lower portions to and communicating with said tank, the latter having an outlet at the top thereof, aligning bearings in said casing, a shaft mounted in said bearings, a rotary element fast on the lower end of said shaft, fixed blades in said upper and lower casing sections above and below said rotary element for preventing rotation of the liquid in which said rotary element is immersed, a stationary suction pipe having its lower portion enclosing the lower portion of said shaft and opening into said rotary element, and means for actuating said rotary element and its shaft, the bottom section of said runner casing being detachable from the upper section thereof and from the bottom of said tank.

8. A rotary vacuum pump comprising a tank, a runner casing communicating therewith and having mounted therein an eduction nozzle secured to a vertically positioned shaft rotatably mounted in said runner casing, said nozzle coacting with upper and lower fixed blades for preventing rotation of liquid, and a stationary suction pipe partially enclosing said shaft and having an opening communicating with said eduction nozzle, the lower portion of said runner casing being detachable, and carrying said lower fixed blades.

9. A rotary vacuum pump comprising a tank, a runner casing communicating therewith and having mounted therein a plurality of elliptically shaped eduction nozzles immersed in a liquid contained in said tank and runner casing, a shaft carrying said eduction nozzles, the major axes of said nozzles being arranged at an angle to the plane of rotation thereof to impart a translatory motion to the liquid parallel to the axis of rotation of said nozzles, a stationary suction pipe having its lower portion enclosing the lower portion of said shaft and communicating with said eduction nozzles, and a plurality of upper and lower fixed blades coacting with said nozzles and mounted in said runner casing for preventing the rotation of liquid therein.

10. In a device of the character stated, a tank, a sectional runner casing having its upper and lower portions communicating with said tank, a vertically disposed shaft in said runner casing, a submerged rotary element secured to the lower end of said shaft and having elliptical nozzles, having their major axes inclined to their plane of rotation, a suction pipe surrounding said shaft and communicating at its lower end with said rotary element, fixed blades above said rotary element in the upper section of said sectional runner casing, and fixed blades below said rotary element in the lower section of said runner casing, said lower section being removable from said upper section and said tank.

JOHN F. METTEN.
